UNITED STATES PATENT OFFICE

JACQUES RISLER, OF PARIS, FRANCE, ASSIGNOR TO RISLER CORPORATION OF AMERICA,
OF KANSAS CITY, MISSOURI, A CORPORATION OF DELAWARE

ELECTRIC LAMP

No Drawing. Application filed August 8, 1927, Serial No. 211,426, and in France November 2, 1926.

My present invention relates to electric lamps, and more particularly to luminous electrical discharge tubes.

The light emitted by luminous electrical discharge tubes has heretofore had the disadvantage, for most purposes, of showing some predominant color. It is the object of my present invention to provide a luminous electrical discharge tube which emits light

10 that is approximately white to the eye.

I have discovered that when an electrical discharge is passed through a mixture of substantially 70% neon and 30% helium under reduced pressure an approximately 15 white light is produced. My invention consists of an electrical discharge tube filled under reduced pressure with a mixture of substantially 70% neon and 30% helium.

The discharge tube itself may be 20 constructed according to any of the several known methods and designs for making luminous electrical discharge tubes. The total pressure of the gaseous mixture in the tube should preferably be between 10^{-4} and 25 5 mm. of mercury.

What I claim and desire to secure by Letters Patent is:

A luminous electrical discharge tube containing a mixture of substantially 70% neon and 30% helium at a total pressure of between 10^{-4} and 5 mm. of mercury.

In testimony whereof I affix my signature.

JACQUES RISLER.
